UNITED STATES PATENT OFFICE.

ROLLIN DAVIS OSGOOD, OF BIRMINGHAM, ALABAMA.

MANIPULATOR FOR ROLLING MILLS.

Application filed July 10, 1923. Serial No. 650,610.

To all whom it may concern:

Be it known that I, ROLLIN DAVIS OSGOOD, a citizen of the United States, and residing at Birmingham, Jefferson County, and State of Alabama, have invented certain new and useful Improvements in Manipulators for Rolling Mills, of which the following is a specification.

My invention relates to improvements in mechanism for turning blooms, billets, blanks and similar work which is run out between the different stands of a rolling mill.

One object of the invention is to provide a manipulator which will exert a forcible grip on the bloom or other blank regardless of the cross-sectional shape or dimensions of the work.

A further object is to provide such a mechanism which after it has turned the bloom will move laterally from the work to a position clear of the path of travel of the bloom along the roller table thereby avoiding any interference or jamming of the work against the manipulator parts, even though the rolled section may have widely forked ends.

Heretofore manipulators have been constructed with a lifting member and a counterweighted holding member arranged to be held in contact with the bloom or rolled section by means of a cam co-acting with the counterweighted holding member. This counterweighting holding member has in some cases been provided with an anti-friction roller which contacts with the bloom, and after the bloom has been turned and transferred the same has been fed laterally while in contact with the holding member and the lifting member. With such an arrangement, if the bloom has forked ends or is otherwise distorted or of uneven section, when the bloom is moved or fed longitudinally by the mill rolls there is apt to be destructive interference between the bloom and the parts of the manipulator which will cause jamming of the work and perhaps breakage of the manipulator, this making it necessary to shut down the mill for repairs.

My improved manipulator overcomes these disadvantages because after the bloom has been turned the gripping mechanism I employ is adapted to disappear, that is to say, it is adapted to get out of the way of the work.

The invention is illustrated in the accompanying drawings in which Fig. 1 is a top plan showing the manipulator and its operating mechanism with the bloom engaging parts drawn to the extreme left or "clear" position.

Fig. 2 is a side elevation partly in section showing the manipulator in its advanced position ready to engage a bloom on a run-out table, the dotted lines illustrating the manipulator parts in their retracted or clear position;

Fig. 3 is a cross-section on line 3—3 of Fig. 2 illustrating a friction device for retarding the movement of the manipulator carriage;

Figs. 4, 5 and 6 illustrate different positions of the manipulator parts in turning and transferring a bloom or billet.

Referring to the drawings in detail, 10 is a base on which is secured a pair of operating cylinders 12 and 14 provided with suitable pistons for reciprocating the piston rod 16 and cross-head 17 which is connected by long pitman rods 18 with a pin 20 carried on the arm of a gripping member 22 which gripping member is formed with a bloom engaging portion 24. The gripping member 22 is pivotally mounted on a stud 26 secured in the free end of a bent lever 28 which is secured to a shaft 30 mounted in a carriage 32. The carriage 32 rides in suitable ways 34 secured to the bed 10. Loosely mounted on the shaft 30 is a tongue 36 which, in full line position shown in Figs. 2 and 6, rests on a cross-flange 38 of the carriage.

The tongue 36 is formed with a flat bloom engaging surface 40 and also with a tooth or projection 42 adapted to co-act with a dog 44 which is pivotally mounted on a pin 46 secured to the bent lever 28. The dog 44 is formed with a tail 48 which is adapted to strike a stop 50 formed on the carriage to disengage the dog from the projection 42 after the bloom has been turned and transferred. This means for engaging and disengaging the tongue 36 from the bent lever 28 permits the manipulator to clear the work after such work has been turned as will more fully appear hereinafter.

Secured to one end of the carriage 32 is a friction bar 52, this bar being connected by means of a pin 54 passing through suit-

- able lugs formed at one end of the carriage as shown. The friction bar slides through a housing 56 which is provided with a friction block 58 which is yieldingly held in contact with the friction bar 52 by means of compression springs 60 encircling the outer ends of bolts 62 which tend to press the bar 64 firmly against the friction block 58 as clearly shown in Fig. 3.
- 10 In operation, assuming that the parts are in full line position, shown in Fig. 2, when the piston rod 16 moves to the left, the connecting rods 18 will be pulled thus rocking the gripping member 22 about the pivot 26 which action will bring the portion 24 of the gripping member into contact with the bloom B as illustrated in Fig. 4. During this movement the friction exerted by the spring 60 on the bar 52 prevents the carriage 20 from moving to the left. Further pulling on the pitman rods 18 will rock both the tongue 36 and the bent lever 28 about the shaft 30 in a counter-clockwise direction due to the engagement of the dog 44 with the tooth 42.
- 25 This rotation will turn the bloom to the upright position shown dotted and indicated at B' in Figs. 2 and 6. Toward the end of this movement the bent lever 28 is rocked to such position that the tail 48 of the dog 30 strikes the projection 50 on the carriage and disengages the tongue 36 from the bent lever. This permits the tongue 36 to move to the horizontal position as illustrated in Fig. 6 where it will come to rest against the 35 flanged cross-member 38 with its upper surface 40 in a plane lower than the bottom edge b of the bloom. The continued pull of connecting rods 18 will now pull the gripping mechanism and carriage 32 to a position 40 clear of the table, as shown by the dotted lines in Fig. 2, leaving the bloom B' as indicated by the dotted lines in Figs. 2 and 4, supported in the usual manner on rollers R. Thus it is clear that there is 45 no chance of interference between the bloom and any of the bloom-engaging members of the manipulator even though the ends of the bloom are distorted by their pass through the mill rolls.
- 50 After the bloom B', for example, has been fed longitudinally on a run-out table, and it is desired to turn up another bloom B, as shown for example in Fig. 2, the piston rod will be moved to the right which will cause 55 the gripping member 22 to swing on its pivot 26 until the portion 24 strikes the lug 29 on the bent lever 28, as shown in Fig. 6. The lever 28 and gripping member will now rock together about the shaft 30, without 60 sliding the carriage, due to the friction on the bar 52, whereupon the dog 44 will drop beyond the tooth 42 on the tongue 36 when the bent lever reaches its upright position. When the lever reaches its upright position,

it strikes a suitable shoulder 37 on the tongue 65 and further movement of the piston rod then causes the carriage to move to the right to the position shown in full lines in Fig. 2 where the upright portion of said bent lever 70 engages the bloom to be turned.

The connecting rods 18 will again be pulled to the left which will cause the gripping member 22 to swing on its pivot 26 and grasp the billet B whereupon the above described 75 cycle will take place again.

Though I have described with great particularity the specific embodiment of the invention herein shown, it is not to be construed that I am limited thereto as changes 80 and substitution of equivalents may be made by those skilled in the art without departing from the invention.

Throughout the description I have referred to the manipulator mechanism as one for turning up a bloom. It is to be understood that the mechanism is adapted for use on various roll sections and the term "bloom" as used in the claims is intended to apply with equal force to ingots, billets, 85 slabs, plates and similar blanks. 90

What I claim is:

1. A manipulator having members arranged to grip and turn a bloom, means for releasing the grip of said members on the bloom and means to move said gripping 95 members clear of the article turned.

2. A manipulator having members for engagement with a bloom, and power actuated means for pulling one of said members to grip or force the bloom against another of the members while turning the bloom and means for releasing the grip on the bloom after it has been turned. 100

3. A manipulator including two members movable about a common center, a gripping member pivoted to one of said members and power means for rocking the pivoted member to bring it into gripping engagement with the bloom. 105

4. A manipulator for turning blooms, comprising a slidably mounted carriage, a friction device for retarding the movement of said carriage, a gripping member, a pair of bloom-engaging members pivoted on said carriage, means for engaging and disengaging said members from one another so that the carriage can be moved to a position to avoid interference between the bloom and the aforesaid members. 110

5. A manipulator including a pair of 120 bloom-engaging members movable about a common axis, an intermediate member for connecting or disconnecting said bloom-engaging members with one another, a pivoted gripping member carried by one of the aforesaid bloom-engaging members and means for rocking said gripping member on its pivot to firmly grip the bloom. 125

6. A manipulator including a slidably mounted carriage, a lever pivoted on said carriage, a tongue pivoted on the same center with said lever, a dog carried by said lever and a projection on said tongue whereby the two can be moved together or independently, a gripping member pivoted on the free end of said lever and power means for moving said gripping member on its pivot to grip the bloom between it and said tongue and also for turning said lever and tongue on their pivot to turn the bloom. 10
- In witness whereof, I have hereunto signed my name.

ROLLIN DAVIS OSGOOD
